DESIGN FOR A GOLF CLUB HEAD

Charles G. Jansky, Berwyn, Ill., assignor to General Sports Mfg. Co., Chicago, Ill., a corporation of Delaware

Application November 30, 1934, Serial No. 54,196

Term of patent 7 years

To all whom it may concern:

Be it known that I, Charles G. Jansky, a citizen of the United States, residing at Berwyn, in the county of Cook and State of Illinois, have invented a new, original, and ornamental Design for Golf Club Heads, of which the following is a specification, reference being had to the accompanying drawing, forming part thereof.

Fig. 1 is a front elevation of a golf club head embodying my design;

Fig. 2 is a rear elevation thereof;

Fig. 3 is a bottom view thereof, showing the inserted sole plate; and

Figs. 4 and 5 are rearwardly looking transverse sections taken on the lines 4-4 and 5-5 respectively of Fig. 3, a portion of the shank being broken away.

I claim:

The ornamental design for a golf club head, as shown.

In witness whereof, I hereunto subscribe my name, this 22nd day of November, 1934.

CHARLES G. JANSKY.
